CLAIM

The ornamental design for an umbrella crank housing and battery assembly as shown and described.

DESCRIPTION

FIG. 1 shows an umbrella crank housing and battery assembly embodying the new design thereof, shown in the context of an umbrella.

FIG. 2 is a perspective view of the umbrella crank housing and battery assembly design illustrated in FIG. 1.

FIG. 3 is a front view of the umbrella crank housing and battery assembly design of FIG. 2.

FIG. 4 is a rear view of the umbrella crank housing and battery assembly design of FIG. 2.

FIG. 5 is a first side view of the umbrella crank housing and battery assembly design of FIG. 2.

FIG. 6 is a second side view of the umbrella crank housing and battery assembly design of FIG. 2.

FIG. 7 is a top view of the umbrella crank housing and battery assembly design of FIG. 2; and,

FIG. 8 is a bottom view of the umbrella crank housing and battery assembly design of FIG. 2.

The broken lines depict portions of the article and environment that form no part of the claimed design.
